KEY OPERATED CONTROL MEANS FOR
RADIO RECEIVING SETSErwin R. Stockle, Milwaukee, Wis., assignor to
Central Radio Laboratories, Inc., Milwaukee,
Wis., a corporation of Wisconsin

Application November 25, 1932, Serial No. 644,289

6 Claims. (Cl. 201—55)

This invention relates to an improvement in control devices for radio receiving sets and is especially applicable to that class of sets employed on automobiles.

The control device of the present invention is of the type which combines a volume control and an "on" and "off" switch and the object of the present invention is to provide a device of this character wherein the switch is turned "on" and "off" and the variable resistance of the volume control is adjusted by means of a key. The arrangement is such that the first turning movement of the key following its insertion brings about an actuation of the "on" and "off" switch to throw it to "on" position and thereby energize the set. Continued turning movement of the key in the same direction cuts out resistance incorporated in the volume control to increase the volume as desired. As the key is turned back toward its original position more resistance is cut into the circuit to thereby reduce the volume as may be desired.

Another object of the present invention is to provide a control device of this character which is simple and durable in its construction, closely and compactly organized, reliable and effective in operation, easy and comparatively inexpensive to manufacture, and adapted to be conveniently installed on a suitable panel or bracket.

Other objects reside in certain novel features of the construction, arrangement and combination of parts which will be hereinafter more fully described and particularly pointed out in the appended claims, reference being had to the accompanying drawings forming a part of this specification, and in which:

Figure 1 is a view in elevation showing the volume control device and "on" and "off" switch together with a portion of a housing therefor, the front plate of the housing and the parts carried thereby being omitted;

Figure 2 is a similar view showing the front plate of the housing and the parts carried thereby, portions of the front plate being broken away for the sake of illustration;

Figure 3 is a view in elevation showing the opposite side of the front plate of the housing from that shown in Figure 2, and also illustrating the parts disposed adjacent the inside face of the front plate;

Figure 4 is a view in section taken on line 4—4 of Figure 1, parts being shown in elevation for the sake of simplicity in illustration;

Figure 5 is a similar view on line 5—5 of Figure 1;

Figure 6 is a sectional view taken on line 6—6 of Figure 4; and

Figure 7 shows the housing in rear elevation.

Referring to the drawings, the numeral 1 designates a housing which may be molded from insulating material and has a chamber or recess 2 formed within a projection 3 thereof and utilized to accommodate the "on" and "off" switch designated generally at 5. The housing also provides a chamber designated generally at 4 in 10 which is mounted and housed the variable resistance of the volume control device designated generally at V. The chamber 4 opens outwardly through one side of the housing but in the assembly it is closed by means of a removable 15 front plate 5 having a surfacing 6 of insulating material and suitably secured to the housing by fastening devices designated diagrammatically at 7.

The "on" and "off" switch comprises a fixed 20 contact 10 having its shank extending through the housing and riveted as at 11 exteriorly thereof to a binding post 12. Cooperable with this fixed contact is a movable contact 13. The contact 13 is constructed of sheet metal and is 25 mounted for swinging movement on a stud 14 interconnected with the housing and having a portion projecting exteriorly thereof and riveted as at 15 to a binding post 16. The interconnection of this movable contact 13 with the stud 14 30 is such as to allow free swinging movement of the movable contact. The portion of the movable contact which engages the fixed contact 10 has oppositely disposed upwardly flaring guiding lugs 17 designed to insure overlapping engagement 35 of the movable contact with the fixed contact 10 and with an abutment 18 formed as an integral part of the housing. A portion 19 of the movable contact is depressed or struck down to form a stop 40 which limits the extent to which the movable contact may overlap and engage the fixed contact 10 or the abutment 18. This movable contact also constitutes one arm or link of a toggle, the other arm or link of which is designated at 20. The toggle member or link 20 is also supported for 45 swinging movement on the stud 14 and may be held against displacement therefrom by means of a retaining clip 21. This toggle member 20 is preferably constructed of insulating material and is connected to one leg of a toggle spring 22, the other leg of this toggle spring 22 being interconnected with a lug 23 struck from the movable contact member. By shifting the toggle member 20 in one direction or the other to a predetermined extent, the action of the spring 22 may be 50

55

reversed so that it will swing the movable contact member 13 in one direction or the other with a snap action, the direction of swinging of the movable contact member depending upon the direction in which the toggle member 20 is swung. In cross section the toggle member 20 is generally U-shaped in that its body portion is provided with a pair of spaced parallel side flanges 25 which extend outwardly toward the chamber 4.

10 The volume control device consists of a resistor 30 suitably secured against a seat 31 provided therefor within the chamber 4. The resistor is of the type in which a suitable backing sheet or strip in the form of a split annulus is sprayed or otherwise coated with graphite. The ends of the graphite resistor are secured by rivets 32 passing through the housing 1 to binding posts 33 and 34. Overlying the resistor is a metallic contact strip 35 of arcuate form, the ends of which are integral with the branches 36 of a supporting arm 38. The supporting arm 38 is secured in position upon seat 39 provided therefor, this securing being effected by means of a rivet 40 which also electrically connects the supporting arm and consequently the metallic contact strip with a binding post 41 disposed exteriorly of the housing, the rivet passing through the material of the housing as shown in Figure 4. The supporting arm 38 tends to maintain the contact strip 35 spaced away from the resistor although the contact strip 38 is inherently resilient and may be displaced or flexed into contact with the resistor throughout its extent. It is obvious that the point to which the contact strip 35 engages the resistor determines the extent to which the resistor 30 is incorporated in the circuit.

Means is provided for flexing various portions of the contact strip 35 into engagement with the resistor and comprises a pressure button 45 carried by a radial extension 46 of a disc 47. The disc 47 is connected to and rotated with the core 48 of a lock designated generally at L. A stop lug 49 is struck from the cover 5 and projects into a slot 50 formed in the disc 47, the lug 49 being engageable with the ends of the slot 50 to limit the rotation of the disc 47 and consequently of the pressure button 45 in either direction. The lock L includes a bushing 51 in which the core 48 is rotatably supported. The inner end of this bushing is received in a central opening provided in the front plate 5 and it is suitably connected or fastened to the marginal edge of such opening as indicated at 52. The bushing 51 is externally threaded and its external threads are engaged by the internal threads of a sleeve 53 which completes the enclosure of the lock L and also provides a nut structure cooperable with the front plate in securing the device in position on a panel or bracket. It is to be understood in this connection that the bushing 51 passes through an opening in such a panel or bracket and that the panel or bracket is clamped between the inner end of the sleeve 53 and the front plate 5 of the main housing.

65 The outer end of the sleeve 53 has an inwardly directed annular flange 55 integral therewith and confining the edge of a disc 56 formed with a key slot 57. The flange 55 has a notch 58a aligned with and forming a continuation of the key slot 57 in order that the key may be inserted and withdrawn in one position only wherein the "on" and "off" switch has been turned to "off" position.

70 The core 48 is in the form of a cylindrical plug and has a reduced extension 48' projecting 75 through the inner end of the bushing 51 and

riveted to the disc 47. Forwardly the plug or core 48 has a longitudinal slot 58 designed to receive a portion of the key designated at 59. This plug 48 and the bushing 51 may be provided with conventional types of tumblers normally holding the plug against rotation but shifted by the key to release the plug for rotation when the key is inserted in the slot thereof. Such details of the locking mechanism are not shown as they are well known and widely used and per se form no part of this invention. In fact, in many instances, it may be desirable to omit them and merely rely on the configuration of the keyhole slot to preclude operation in a practical manner except by use of the proper key.

15 In order that the key may be utilized to actuate the "on" and "off" switch as well as to actuate the volume control the disc 47 has a pin 60 secured thereto and extending longitudinally through the housing and into the space between the flanges 25 of the toggle link 21. With this arrangement when the key is inserted and turned the initial turning movement moves the pin 60, and such movement of the pin 60 is transmitted through one of the flanges 25 to the toggle link 20 25 to swing this link 20 and cause it to reverse the action of the spring 22 and snap the switch to "on" position, that is to say, the movable contact 13 is shifted with a snap action from a position wherein it engages its abutment 18 to 30 a position wherein it engages the fixed contact 10 of the switch. Upon further movement of the disc 47 under the influence of the key the pin simply travels out of the space between the flanges 25 and such further turning movement 35 merely shifts the pressure button 45 and varies the action of the volume control. However, upon return of the key to its original position the pin 60 reversely actuates the toggle link 21 to cause the switch to be snapped to the "off" position. 40

The key has a cross section or shape corresponding to the contour or formation of the slot 57 and it also has a notch 55 which, when the key is turned away from the notch 58, straddles a portion of the flange 55 thereby preventing 45 withdrawal of the key except in the position wherein the switch is turned off.

While I have shown and described one construction as typical of the manner in which the invention may be embodied, it is to be understood that this construction has been selected merely for the purposes of illustration or example, and that various changes in the size, shape and arrangement of the parts may be made without departing from the spirit of the invention 55 or the scope of the subjoined claims.

The invention claimed is:

1. In combination with a volume control device having a housing and a variable resistance in said housing, a bushing connected to said housing and projecting therefrom, a slotted operating element for the variable resistance mounted in said bushing, a sleeve connected with said bushing and completing the enclosure of said operating element, said sleeve having an end wall provided with a keyhole slot and a key insertable through said keyhole slot and cooperable with said operating element whereby movement of the key throughout its entire range of rotation continuously regulates the action of the variable resistance.

2. The combination with a control means for radio receiving sets including a volume control device, an "on" and "off" switch interlocked with said device to be actuated thereby, operating

- means for said device and a housing enclosing said device, switch and operating means, of a lock having a part interconnected with said operating means for actuating the same, and a 5 key cooperable with the lock whereby movement of the key throughout the entire range of rotation operates said lock and continuously regulates said volume control device, said lock having its enclosure connected to said housing and provided with means adjustably cooperable with the 10 housing for supporting the control means.
3. The combination with a control means for radio receiving sets including a volume control device, an "on" and "off" switch interlocked with 15 said device to be actuated thereby, operating means for said device and a housing enclosing said device, switch and operating means, of a lock having a part interconnected with said operating means for actuating the same, a key cooperable 20 with the lock whereby movement of the key throughout the entire range of rotation operates said lock and continuously regulates said volume control device, said lock having its enclosure consisting of a brushing connected to said housing 25 and containing said movable part, and a sleeve threaded on said bushing and coacting therewith to complete the enclosure and adjustably cooperable with the housing for supporting the control means in position.
4. The combination with a control means for radio receiving sets including a volume control device, an "on" and "off" switch interlocked with 30 said device to be actuated thereby, operating means for said device and a housing enclosing said device, switch and operating means, of a lock having a part interconnected with said operating means for actuating the same, a key cooperable 35 with the lock whereby movement of the key throughout the entire range of rotation operates said lock and continuously regulates said volume control device, said lock having its enclosure consisting of a brushing connected to said housing and containing said movable part, and a sleeve threaded on said bushing and coacting 40 therewith to complete the enclosure and adjust-
- ably cooperable with the housing for supporting the control means in position, said bushing having a disc at one end provided with a keyhole slot through which said key is inserted. 5
5. The combination with a control means for radio receiving sets including a volume control device, an "on" and "off" switch interlocked with 10 said device to be actuated thereby, operating means for said device and a housing enclosing said device, switch and operating means, of a lock having a part interconnected with said operating means for actuating the same, a key cooperable 15 with the lock whereby movement of the key throughout the entire range of rotation operates said lock and continuously regulates said volume control device, said lock having its enclosure consisting of a bushing connected to said housing and containing said movable part, and a sleeve threaded on said bushing and coacting 20 therewith to complete the enclosure and adjustably cooperable with the housing for supporting the control means in position, said bushing having a disc at one end provided with a keyhole slot through which said key is inserted, there being cooperating means between said enclosure 25 and said key to preclude removal of the key except when it is in such position that said switch is off.
6. A control means for radio receiving sets comprising in combination, a revoluble rheostat 30 volume control device an "on" and "off" switch actuated by said device, operating means for said device having a slotted operating element, a housing enclosing said device, switch and operating 35 means, said housing having a key hole slot in alinement with the slot of said element, and a key insertable through said key hole slot and adapted to fit in the slot of said operating element whereby rotation of said key effects the 40 action of the switch and regulates the volume control device, said switch being in the "off" position and said key being removable when said slots are in alinement.

ERWIN R. STOEKLE. 45
